DESIGN FOR A SLIPPER BAG OR SIMILAR ARTICLE

John E. Disch, Dolgeville, N. Y.

Application January 5, 1937, Serial No. 66,903

Term of patent 3½ years

To all whom it may concern:

Be it known that I, John E. Disch, a citizen of the United States, residing in Dolgeville, in Herkimer County, in the State of New York, have invented a new, original, and ornamental Design for a Slipper Bag or Similar Article, of which the following is a specification, reference being had to the accompanying drawing, forming part thereof:

bag or similar article in closed position showing my new design;

Figure 2 is a front perspective view thereof in open position.

I claim:

The ornamental design for a slipper bag or similar article, substantially as shown and described.

JOHN E. DISCH.
